R. F. GOWEN

RADIO PANEL BOARD

Filed May 2, 1921

INVENTOR

Robert F. Gowen

BY his ATTORNEY S.

Darby & Darby

UNITED STATES PATENT OFFICE.

ROBERT F. GOWEN, OF NEW YORK, N. Y., ASSIGNOR TO DE FOREST RADIO TELEPHONE & TELEGRAPH COMPANY, OF NEW YORK, N. Y., A CORPORATION OF DELAWARE.

RADIO PANEL BOARD.

Application filed May 2, 1921. Serial No. 466,352.

This invention relates to radio panel boards and it has for its object the provision of a panel unit which can be readily supported in different positions and which may be built up to any desired dimensions for supporting radio instruments thereon. A further object includes the provision of easily demountable means whereby my improved panel board may be readily supported and fastened in either a vertical position or may be used as a stand or table.

Further objects will appear hereinafter from the description and claims, and I attain these results by the construction illustrated in the accompanying drawing, in which—

Fig. 1 is a view in elevation of a unit panel;

Fig. 2 is a view in perspective wherein a number of radio panels are joined side by side;

Fig. 3 is a view of one of the readily detachable supports, and

Fig. 4 is a view of one of the securing brackets.

Similar numerals refer to similar parts throughout the several views.

My improved radio panel board, or instrument support, or unit 10, may be of any desired shape or size, but it is usually of rectangular form for the accommodation of the radio instruments (not shown). This radio panel or unit is provided with two or more supports, or extensions 11, which are provided with securing means, consisting, in the preferred form, of a dowel pin 12 and a bolt 13 or equivalent construction. The bolt 13 is usually provided with a securing nut 14, and by aid of these securing means the extensions 11 are fastened, preferably at the corners of the radio unit in bores or holes 19 and 20. When it is desired to use the radio panel in a vertical position, as illustrated for example in Fig. 1, but two supports are required, and these may conveniently be firmly affixed at their free ends, to the floor by means of holding brackets, consisting of suitable plates, as illustrated for example in Fig. 4. These brackets may conform to the outlines of the support and may be provided with a base 15, having therein holes 16 for screws or bolts.

When it is desired to use my radio panel

in a horizontal position, or as a table, I may dispense with the holding brackets and use four supports as legs. In this manner a single unit may be so used, or several units may be joined and suitably fastened or hooked together, if desired, to form a single enlarged radio panel. By reason of the shape and position of the supports, any number of units may be united, either in a horizontal or in a vertical position as is plainly evident from an inspection of the drawing.

By means of my invention, I am enabled to quickly and conveniently build up any sized radio panel, either of the vertical type, or horizontally, and to arrange the same, as may be desired, without the expense of redesigning and building new units for each specific case or need. By my construction I am also enabled to quickly dismount my radio panel and to convert the same from the vertical type panel to the horizontal form or vice versa. And while I have disclosed a specific embodiment of my invention, I do not thereby desire to be understood as having thus limited myself, as various modifications coming wholly within the scope and spirit of my invention may suggest themselves to those versed in the art.

What I claim, therefore, as new and useful, and of my own invention and desire to secure by Letters Patent, is:—

1. In radio panel boards, the combination with a panel unit of supporting extensions for positioning said panels vertically and horizontally, said extensions detachably secured at right angles to said unit for readily grouping several units.

2. A radio panel unit comprising a panel board having a plurality of bores, a plurality of supporting extensions for said panel board, projections extending from said extensions for fitting into said bores to locate said supporting extensions at predetermined points and in predetermined positions, means for fastening said extensions to said panel board, and means for securing said extensions against displacement.

In testimony whereof I have hereunto set my hand on this 29th day of April, A. D. 1921.

ROBERT F. GOWEN.
